SPRAY NOZZLE

Dietrick Strahman, Livingston, N. J., assignor to
 Klingerit, Inc., New York, N. Y., a corporation
 of New York

Application November 9, 1950, Serial No. 194,877

8 Claims. (Cl. 299—131)

1

This invention relates to a combined valve and water spray nozzle of the type in which the valve is biased towards closed position.

For convenience of operation and maximum economy of water, it is desirable for certain uses to have a water spray nozzle combined with a positive closing valve that is biased towards closed position so that when the spray nozzle is not actually being used, the flow of water is automatically and completely shut off. The present invention which embodies such a spray nozzle is provided with a pistol-grip handle and operating lever extending beside the handle and operated by a so-called "squeeze grip."

In the form shown of the present invention, the type of spray produced by the nozzle is controlled by a metering pin located axially within the nozzle and carrying a cylindrical valve member which engages a valve seat immediately to the rear of the nozzle and extending about the metering pin, the position of the forward end of the metering pin relative to the nozzle and the degree of opening of the valve controlling the type and volume of spray. The metering pin is moved rearwardly by the operating lever, and the connection between the lever and metering pin is adjustable so that, when the lever is moved against the pistol-grip handle as in normal operating position, the metering pin and valve are moved rearwardly the proper amount for the particular type of spray desired. This adjustment once having been made, the same character and volume of spray may be obtained repeatedly by moving the operating lever against the grip.

As described herein, applicant's construction includes a rubber cover for protecting the spray nozzle against damage, which is held in place solely by the interfitting of the cover and housing, and which may be removed and replaced without the use of tools or disassembly of the housing and without damage to the cover.

An object of the present invention is to provide a combined valve and spray nozzle of the type described in which the type and volume of spray are controlled by a valve and metering pin; to provide such a nozzle in which the same character of spray may be easily obtained in successive uses of the nozzle without the necessity of adjustment for each use; and to provide a generally improved valve and spray nozzle which is simply and easily manufactured and dependable and convenient in operation.

Other objects of the invention are to provide a combined valve and spray nozzle of simplified construction in which most of the working parts

2

are contained within a conveniently removed sub-assembly, and to provide a rubber cover for the housing of such a nozzle that is easily removable and replaceable.

Other objects and objects relating to economies of manufacture and use will be more apparent from the detailed description to follow.

My invention is clearly defined in the appended claims. Where parts are, for clarity and convenience, referred to on the basis of their oriented position shown in the accompanying drawing, no limitation as to positioning of the entire structure is to be implied, since it will be understood that the entire structure may be used in any position. Also in both the description and the claims, parts at times may be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Fig. 1 is a vertical section taken generally through the axis of the spray nozzle.

Fig. 2 is an enlarged, transverse, vertical section taken on the line 2—2 of Fig. 1.

Fig. 3 is an enlarged, fragmentary, transverse section taken generally on the line 3—3 of Fig. 1.

Fig. 4 is an enlarged, fragmentary section similar to Fig. 1 and showing the metering pin and valve in position to produce a mistlike spray.

Fig. 5 is a view similar to Fig. 4 but with the metering pin and valve in position to produce a medium spray.

Fig. 6 is a view similar to Fig. 4 showing the metering pin and valve in position to produce a coarse spray or stream.

Fig. 7 is a perspective view of the rubber cover.

Referring now to the drawings, the combined valve and spray nozzle of the present invention has a unitary, generally T-shaped housing 10 consisting of a horizontal bore portion 11 and a pistol-grip portion 12 intersecting the bore portion 11 between its ends. An operating lever 14 is pivotally mounted on the rear side of the pistol-grip portion 12 and controls the flow of water through the nozzle, the lever being actuated by movement towards the portion 12 of the housing. The specific construction and operation of the lever 14 will be explained in more detail hereinafter.

The bore portion 11 of the housing is provided with a bore 15, the forward end (left end

as viewed in the drawings) of which threadedly receives a nozzle 16 which has a central aperture 17 coaxial with the bore. The bore 15 has a radial, inwardly projecting step 19 towards the rear end of the bore, and the bore may have a rearward extension 18 beyond the step 19 and of the reduced diameter of the stepped portion of the bore.

The pistol-grip portion 12 of the housing 10 is provided with a longitudinal inlet passage 20 intersecting the horizontal bore a short distance behind the nozzle 16. The lower end of the inlet passage 20 may be threaded to receive a hose adapter 21.

A metering pin 22 is axially located within the bore 15 of the housing, the forward tapered end 23 of the pin being received within the nozzle 16 at the forward end of the bore. A circular valve member 24 is coaxially mounted on the metering pin a short distance behind the tapered end 23 thereof, the valve member having a circularly grooved, forward face forming a forwardly extending peripheral flange 25 for engaging a valve seat. The metering pin is normally biased forwardly (to the left as viewed in the drawings) so as to urge the peripheral flange 25 of the valve member 24 against a resilient rubber or rubberlike annular valve seat 26 positioned against the rear side of the nozzle 16. Preferably, the nozzle 16 has a rearwardly directed flange portion extending about the aperture 17 to aid in holding the valve seat 26 against displacement.

The metering pin 22 is axially supported and guided in the bore 15 by a generally cylindrical stuffing box 29 received within the bore and a cylindrical plug 30 received within the rear extension 18 of the bore. The stuffing box 29 has an outer diameter which is a sliding fit within the bore 15, and the forward end of the stuffing box is provided with a peripheral step 31 to receive an annular, resilient rubber or rubberlike packing ring 32 and form a fluid seal between the bore and the stuffing box.

The stuffing box 29 is provided with an axial hole 34 for slidably receiving the metering pin 22 and a packing chamber 35 receiving resilient packing 36 for forming a fluid seal about the metering pin. The packing 36 is held in sealing relation above the metering pin by an annular follower ring 37 and a helical compression spring 39 extending about the metering pin. The rear end of the packing chamber 35 is closed by an annular plate 40 apertured to receive the metering pin and held in place by swaging in the side wall of the stuffing box.

The stuffing box 29 is held against the step portion 19 of the bore 15 by a cagelike cylindrical spacer 41 extending between the valve seat 26 and the forward end of the stuffing box. The construction is such that, upon screwing the nozzle 16 into the forward end of the housing 10, the spacer bears against the packing ring 32 of the stuffing box so as to hold the stuffing box against the step 19 and, at the same time, laterally expand the packing to form a fluid seal between the stuffing box and the bore. The forward end of the spacer 41 compresses and laterally expands the outer peripheral portion of the valve seat 26 so as to form a fluid seal about the periphery of the valve seat. The spacer 41 is provided with one or more large holes through which fluid passing from the inlet passage 20 into the bore 15 passes and a helical compression spring 42 extending about the metering pin 22 between the stuffing box 29 and the valve member 24 biases

the metering pin and valve member forwardly. This spring is located within, but not connected with, the spacer 41.

A collar 44 is threadedly received on the metering pin 22 behind the stuffing box 29. This collar which is generally cylindrical has a pair of diametrically opposed slots 45, 45 extending chordally of the collar and receiving the parallel ends of a bifurcated valve-actuating portion 46 of the operating lever 14.

The operating lever 14 is pivotally mounted on the outside of the housing 10 at the intersection of the horizontal bore portion 11 and the pistol-grip portion 12 by a pivot pin 43, and an arm portion 48 of the lever extends downwardly to the rear of, and spaced somewhat from, the pistol-grip portion. The arrangement is such that, upon moving the arm portion 48 of lever 14 towards the portion 12 of the housing, the metering pin 22 and valve member 24 are moved rearwardly so as to open the valve and provide a fluid spray through the nozzle 16.

The cylindrical plug 30, which is slidably received within the rear extension 18 of the bore 15, is non-rotatively secured to the rear end of the metering pin 22 by a transverse pin 47 extending through these parts. The rear end of the plug 30 may be provided with a transverse slot 49 for receiving a screw driver or like tool for rotating the metering pin 22. Since the collar 44 is held against rotation by engagement of the bifurcated portions 46, 46 of the operating lever in the slots 45, 45, rotation of the metering pin 22 serves to move the collar axially along the metering pin in either direction so as to adjust the initial position of the lever and control its spacing from the rear side of the pistol-grip portion 12 of the housing.

Since the grip portion 12 of the housing limits the opening movement of the operating lever 14, the degree to which the metering pin 22 may be moved rearwardly upon operation may be positively controlled in this manner; e. g., the further that the collar 44 is moved forwardly on the metering pin 22, the further the arm portion of the operating lever 14 is moved away from the pistol-grip portion 12 of the housing, and the further the metering pin 22 is moved rearwardly when the lever is moved against the pistol-grip portion 12 of the housing.

The character of the spray is controlled by the position of the tapered forward end 23 of the metering pin within the nozzle 16 and also to some extent by the degree of opening of the valve. As the metering pin 22 is moved rearwardly, the valve member 24 is withdrawn from the valve seat 26, the parts being in the general position indicated in Fig. 4 and producing a fine, mistlike spray.

As the metering pin is drawn rearwardly further, the character of the spray changes to a light spray which becomes coarser as the metering pin 22 reaches the position indicated in Fig. 5. As the metering pin is further withdrawn to the position indicated in Fig. 6, the spray becomes a more or less solid stream.

By adjusting the position of the collar 44 on the metering pin 22, the distance that the metering pin is drawn rearwardly when the spray is operated is controlled and, thus, the character of the spray is determined. After once having been adjusted, the same type of spray can be obtained upon each operation until the adjustment is changed for any reason.

For prolonged spraying, a pivoted loop 50 is

provided on the end of the portion 12 of the housing, which may be rotated into position over the end of the operating lever 14 to hold the lever against the portion 12 and thus hold the parts of the spray nozzle in operating position.

The spray nozzle is provided with a resilient moulded rubber jacket or cover 51 which serves to protect the spray nozzle against damage and serves to prevent scratching of other objects by the spray nozzle. This jacket, which is shown in Fig. 7, is shaped to overlie the housing 10 and nozzle 16 and has openings coinciding with each end of the bore 15 and the outer end of the inlet passage 20. The jacket 51 is provided with a slot 52 extending for a short distance along the rear side of the pistol-grip portion and underside of the horizontal bore portion from the intersection thereof. The slot 52 provides clearance for pivotal movement of the operating lever 14, including the bifurcated portion 46. An additional feature of this jacket is that the jacket may be applied or removed from the spray nozzle housing 10 without disassembly of the housing and unit damaging the jacket. This is accomplished by passing the pistol-grip portion 12 of the housing through the slot 52 of the jacket 51 and downwardly within the corresponding portion of the jacket. The forward or nozzle end of the bore portion 11 of the housing is then entered through the slot 52 and into the corresponding portion of the jacket. The jacket is engaged about the rear end of the bore portion 11 of the housing by stretching this portion of the jacket somewhat so as to pass the rear and central portions of the housing through the slot 52, the jacket then contracting and assuming the position indicated in Fig. 1.

The operating portions of the spray nozzle may be easily disassembled for cleaning, repair, or replacement by withdrawing the pivot pin 43 holding the operating lever to the housing 10 and then withdrawing the operating lever from the collar 44. Then, upon unscrewing the nozzle 16, all of the parts contained within the bore 15 may be withdrawn from the forward end of the bore. The metering pin and stuffing box assembly may then be disassembled if desired. To reassemble the spray nozzle, the disassembly operation is reversed.

I claim:

1. A combined valve and water spray nozzle, comprising: a generally T-shaped housing having a horizontal bore portion and a pistol-grip portion intersecting the horizontal bore portion between its ends, the horizontal bore portion having a generally cylindrical passage formed therein and terminating at its forward end in a valve seat and nozzle, a metering pin axially located within the passage, a valve member mounted on the forward portion of the metering pin, the metering pin being mounted for axial movement within the passage and biased forwardly to seat the valve member against the valve seat, a collar threadedly engaged about the rear portion of the metering pin, an inlet passage in the pistol-grip portion intersecting the passage within the horizontal bore portion, an operating lever pivotally mounted on the housing adjacent the intersection of the horizontal bore portion and the pistol-grip portion and having an arm extending generally parallel and in spaced relation to the rear side of the pistol-grip portion and a second portion operatively engaged with the collar to move it rearwardly upon moving the arm towards the pistol-grip portion of the housing, the collar being ad-

justable longitudinally of the metering pin to determine the character of spray produced when the operating lever is moved against the pistol-grip portion.

2. In a combined valve and spray nozzle, a housing provided with a generally cylindrical bore stepped radially inwardly adjacent its rear end, a nozzle threadedly engaged in the forward end of the bore and having an opening located axially of the bore, a metering pin located axially within the bore and nozzle and having a cylindrical valve member mounted on the forward portion thereof, a generally cylindrical stuffing box fitting within the bore and forming a fluid seal about the metering pin, a resilient annular valve seat immediately behind the nozzle and engaged by the valve member, a packing ring extending about the forward end of the stuffing box, and a cylindrical spacer extending within the bore between the valve seat and the stuffing box to hold the valve seat in position and press upon and radially expand the stuffing box packing ring to form a fluid seal between the stuffing box and the bore.

3. In a combined valve and spray nozzle, a housing provided with a generally cylindrical bore stepped radially inwardly adjacent its rear end, a nozzle threadedly engaged in the forward end of the bore and having an opening located axially of the bore, a metering pin located axially within the bore and nozzle and having a cylindrical valve member mounted on the forward portion thereof, a generally cylindrical stuffing box fitting within the bore and forming a fluid seal about the metering pin, a resilient annular valve seat immediately behind the nozzle and engaged by the valve member, a packing ring extending about an end of the stuffing box and a cylindrical spacer extending within the bore between the valve seat and the stuffing box to hold the valve seat in position and axially compress and laterally expand the stuffing box packing ring to form a fluid seal between the stuffing box and the bore.

4. In a combined valve and water spray nozzle, the combination of a generally T-shaped housing having a horizontal bore portion and a pistol-grip portion intersecting the horizontal bore portion between its ends, and a resilient removable jacket of stretchable rubberlike material of similar form for receiving the housing, the jacket having a slot formed therein extending for a portion of the distance along the rear side of the pistol-grip portion and the underside of the horizontal bore portion from the intersection of these portions.

5. In a combined valve and water spray nozzle, the combination of a generally T-shaped housing having a horizontal bore portion and a pistol-grip portion intersecting the horizontal bore portion between its ends, an operating lever pivotally mounted on the housing at the intersection of the rear side of the pistol-grip portion and the underside of the horizontal bore portion and having a portion extending within the horizontal bore portion a short distance behind the pivotal mounting, and a resilient removable jacket of stretchable rubberlike material of form similar to the housing for receiving the housing, the jacket having a slot formed therein extending for a portion of the distance along the rear side of the pistol-grip portion and the underside of the horizontal bore portion from the pivotal mounting of the operating lever to provide clearance for the operating lever and to permit removing the jacket from the housing.

6. A combined valve and water spray nozzle, comprising: a housing having a bore portion, the

bore portion having a first generally cylindrical passage formed therein and terminating at its forward end in a valve seat and nozzle, a metering pin axially located within the first passage, a valve member mounted on the forward portion of the metering pin, the metering pin being mounted for axial movement within the passage and biased forwardly to seat the valve member against the valve seat, a collar engaged about the rear portion of the metering pin, a second inlet passage in the housing intersecting the first passage within the bore portion, means operatively engaged with the collar to move it rearwardly to retract the metering pin and open the valve an amount determined by position of the collar upon moving said means to a fixed position, the collar being adjustable longitudinally of the metering pin to determine the character of spray produced when the metering pin is retracted, and a lock for holding the collar-engaging means in said fixed position against the bias of the metering pin.

7. A combined valve and water spray nozzle, comprising: a housing having a bore portion, the bore portion having a first generally cylindrical passage formed therein and terminating at its forward end in a valve seat and nozzle, a metering pin axially located within the passage, a valve member mounted on the forward portion of the metering pin, the metering pin being mounted for axial movement within the passage and biased forwardly to seat the valve member against the valve seat, a collar threadedly engaged about the rear portion of the metering pin, a second inlet passage in the housing intersecting the first passage within the bore portion, metering-pin-operating means mounted on the housing and nonrotatably engaging the collar to move it rearwardly to retract the metering pin and open the valve an amount determined by position of the collar upon moving said means to a fixed position, the metering pin being axially rotatable to adjust the collar longitudinally thereof.

8. A combined valve and water spray nozzle, comprising: a generally T-shaped housing having a horizontal bore portion and a pistol-grip portion intersecting the horizontal bore portion between its ends, the horizontal bore portion having a generally cylindrical passage formed therein and terminating at its forward end in a valve seat and nozzle, a metering pin axially located within the passage, a valve member mounted on the forward portion of the metering pin, the metering pin being mounted for axial movement within the passage and biased forwardly to seat the valve member against the valve seat, a collar threadedly engaged about the rear portion of the metering pin, an inlet passage in the pistol-grip portion intersecting the passage within the horizontal bore portion, an operating lever pivotally mounted on the housing adjacent the intersection of the horizontal bore portion and the pistol-grip portion and having an arm extending generally parallel to and in spaced relation to the rear side of the pistol-grip portion, the operating lever having a second portion operatively and nonrotatably engaged with the collar to move it rearwardly upon moving the arm towards the pistol-grip portion of the housing, the metering pin being axially rotatable to adjust the collar longitudinally thereof and movement of the operating lever being limited by the pistol-grip portion of the housing.
